UNITED STATES PATENT OFFICE.

WILLIAM M. WHITING, OF ELIZABETH, NEW JERSEY.

GRAIN-BINDER ELEVATOR.

SPECIFICATION forming part of Letters Patent No. 337,643, dated March 9, 1886.

Application filed October 22, 1884. Serial No. 146,203. (No model.)

To all whom it may concern:

Be it known that I, WILLIAM M. WHITING, a citizen of the United States, residing at Elizabeth, in the county of Union and State 5 of New Jersey, have invented certain new and useful Improvements in Grain-Binder Elevators, of which the following is a specification, reference being had to the accompanying drawings.

10 My improvements relate more particularly to that class of grain-binding harvesters in which the grain is taken from the platform and carried over the main wheel by elevator-belts, and by them delivered to the binding 15 mechanism situated above and outside of the main wheel; and it consists in a fixed shield or guard, which covers the rear edge of the lower elevator-belt and prevents entanglement of the grain with the rollers by which it 20 is driven.

The greatest utility of my invention is developed when the machine is working in longer grain than that for which it was designed, though it is a useful and desirable 25 feature at all times in so far as it prevents dirt, loose straws, or any foreign substance from getting under the edge of the belt and between it and the rollers, where it would pack and accumulate to an injurious extent, 30 and could only be dislodged by stopping the machine and removing the belts from the rollers—an operation consuming much time and detracting greatly from the value of the machine where it has to be often repeated in the 35 field.

In the accompanying drawings, which show so much of a harvester as is necessary to illustrate my invention, Figure 1 is a perspective view of a portion of the elevator-frame of a 40 harvester, showing the elevator and platform belts partly broken away and their relative positions to each other, and also the application of my improved guard to the rear edge of the lower elevator-belt. Fig. 2 is a transverse section through the upper rolls and portions of the elevator-belts; and Fig. 3 is a 45 longitudinal section of the same on the line 3 3 of Fig. 2, as seen by an observer standing above and on the grain side of the elevator and looking in the direction of the arrows.

The elevator-standards A, one only of which

is shown, support in suitable bearings the rollers B' for the upper elevator-belt, B², and rollers C' for the lower elevator-belt, C². These belts are carried upon and driven by 55 the rollers, in the usual manner, in the direction shown by the arrows, taking the grain which is delivered to them by the platform-belt D and carrying it up between their adjacent surfaces, and delivering it upon the pitch-board 60 or binding-table E within easy reach of the packing devices of any suitable binding mechanism. A guard or apron, F, of canvas or metal, fixed at one of its edges f to the elevator-standard, overlaps and protects the rear 65 edge of the lower elevator-belt. It may be fastened at its lower end, f', to a part of the elevator-frame, or a special block or projection attached to the frame for this purpose; but if it is made of metal this attachment 70 may be dispensed with, the edge connection alone being sufficient to sustain it in position. At its upper end, f'', it curves over the upper roller, and is attached to the pitch-board, 75 as shown. Various other methods of attaching and sustaining the guard will readily occur to any skilled person, the one I have shown being the first to suggest itself and the easiest of illustration, though I do not wish to confine myself to it.

The carrier-slats are shown as projecting under the guard; but they may advantageously be shortened and the guard permitted to lie close to or even against the surface of the belt.

When the machine is handling longer grain than it is designed, or, in other words, grain longer than the space between the elevator-standards, the heads must necessarily bend back and drag against the rear standard. 90 This causes a considerable massing of material at the rear edge of the belts, with a strong tendency for some of it to find its way around the edge of and under the belt, where it becomes engaged with and wraps upon the rollers.

I have in practice experienced so much trouble from this source that without any guard I consider the machine as almost useless for long grain.

Having thus described my invention, I claim as my invention—

In a harvesting-machine, the combination, with the elevator-belts, of a fixed guard located between the belts and attached to the frame of the elevator and overlapping the 5 rear edge of the lower or grain-carrying belt and the ends of its rollers, substantially as described.

In testimony whereof I affix my signature in presence of two witnesses.

WILLIAM M. WHITING.
